Primary Examiner — Natasha Vujcic

(57) **CLAIM**

The ornamental design for an air conditioner as shown and described.

DESCRIPTION

The patent or application file contains at least one drawing executed in color. Copies of this patent or patent application publication with color drawing(s) will be provided by the Office upon request and payment of the necessary fee.

1. Air conditioner

1.1 : Front

1.2 : Left

1.3 : Right

1.4 : Top

1.5 : Bottom

1.6 : Perspective

1.1 is the front view; 1.2 is the left view; 1.3 is the right view; 1.4 is the top view; 1.5 is the bottom view; 1.6 is the perspective view; when using the rear view, it is an invisible part, so it is omitted; the product color and the background color are not claimed.

1 Claim, 6 Drawing Sheets
